(57) **CLAIM**

The ornamental design for a beacon housing, substantially
as shown and described.

DESCRIPTION

FIG. 1 is a perspective view of a first beacon housing
incorporating our new design.

FIG. 2 is a perspective view of a second beacon housing
incorporating our new design.

FIG. 3 is a top view of the first beacon housing.

FIG. 4 is a bottom view of the first beacon housing.

FIG. 5 is a front view of the first beacon housing.

FIG. 6 is a back view of the first beacon housing.

FIG. 7 is a first side view of the first beacon housing; and,
FIG. 8 is a second side view of the first beacon housing.
In certain examples, the first side view of the first beacon
housing shown in FIG. 7 is a right side view, and the second
side view of the first beacon housing shown in FIG. 8 is a
left side view. In other examples, the first side view of the
first beacon housing shown in FIG. 7 is a left side view, and
the second side view of the first beacon housing shown in
FIG. 8 is a right side view.

The broken line shown on the beacon housing is included for
the purpose of illustrating portions of the beacon housing
that form no part of the currently claimed design.
